UNITED STATES PATENT OFFICE.

LEVI HOUSTON, OF MONTGOMERY STATION, PENNSYLVANIA.

CIRCULAR SAWING MACHINE.

SPECIFICATION forming part of Letters Patent No. 300,369, dated June 17, 1884.

Application filed April 9, 1884. (No model.)

To all whom it may concern.

Be it known that I, LEVI HOUSTON, of Montgomery Station, in the county of Lycoming and State of Pennsylvania, have invented certain 5 Improvements in Wood-Sawing Machines, of which the following is a specification.

This invention relates to swinging saws; and it consists in providing the swinging frame with a counter-balance arranged, as hereinafter 10 fully set forth and claimed, to assist in carrying the saw forward or backward from a given point after it is manually carried slightly to one or the other side of said point.

Figure 1 is a perspective view of my improved device; Fig. 2, a side elevation of the same.

Swinging saws are generally mounted in pendulous frames provided with a counter-balance weight or spring so arranged as to 20 carry the frame and saw back to their normal position after a cut is made. Such arrangement is objectionable for the reason that the entire effect of the counter-balance must be overcome by the operator in drawing the frame 25 and saw forward to perform the cutting operation, and this resistance, added to that offered by the wood to be cut, necessitates the use of considerable force to draw it forward, the resistance increasing as the saw advances in its 30 cut. Under my plan the counter-balance serves to put the frame nearly in a state of equilibrium, so that it can be moved in either direction with great ease, though being automatically carried in one or the other direction 35 when barely past a given point to one or the other side, means of adjustment being provided so that the action of the counter-balance may be regulated and made to act with greater force in one or the other direction.

40 In the drawings, A A' represent the hangers or brackets, which are secured to the ceiling or overland timbers, and in which is mounted a shaft, B, which in turn carries the band-wheel C and fast and loose pulleys D E, as usual.

45 Loosely hung upon the shaft B, preferably between the hangers A A', is the depending saw hanger or frame F, which is forked at both ends, and carries a shaft, G, at the lower 50 end, on which is mounted a belt-pulley, H,

and saw I. The saw is provided with a guard, L, having a handle, M, by which to move the swinging frame back and forth in the arc of a circle concentric with shaft B. Hanger A has a depending arm, N, provided with a laterally-projecting pin, O, upon which is mounted the hub or sleeve P of the counterweight-arm Q. As shown in Figs. 1 and 2, the pendulous arm is furnished near its upper end with a yoke, R, which extends forward and backward from said arm, and is furnished with perforated ears a, to receive threaded stems or rods b, the inner ends of which are jointed or attached to opposite ends of a chain or cord, S, which passes one or more times about the hub P of counterbalance-arm T, as shown. The stems or rods b are furnished with nuts c outside of the ears a, which serve to tighten the chain or band S upon the hub. By loosening these nuts the arm F may be swung to 70 any desired position without causing a rotation of the hub P, and consequently without moving the counter-weight T; but when tightened by turning up the nuts the chain will bind upon and rotate the hub, causing the 75 counter-weight to move in unison with the pendulous arm or saw-frame. As illustrated in the drawings, the adjustment is such that the counter-weight will be raised vertically 80 into line with pivot-arm Q as the frame or arm F assumes a vertical position, and under such arrangement the force or effect of the weight will be transferred from one direction to the other as the axis of the saw passes a vertical plane passing through the pivotal center of 85 frame F. The change of action in the counter-weight will obviously occur always as the counter-weight passes the vertical plane of its pivotal axis, but by the adjustment above explained the angle at which frame F shall hang 90 at the time of such change and the consequent effect of the counter-weight will be determined. Under the arrangement shown and described the counter-balance serves to hold the saw and saw-frame back in the position 95 shown in full lines in Fig. 2 until drawn forward by hand, the counter-weight offering some, but not a great amount, of resistance until it swings back of its pivot, from which point it aids in carrying the saw forward through 100

the wood. The counter-balance T readily adjusts itself to any movement of the saw-frame F, and, being on an independent shaft, distinct and separate from that of the frame, its weight is not upon said saw-frame and its shaft.

5 The counter balance or weight T is made adjustable upon its arm Q in order to vary the force or action of the weight, and is held at any desired adjustment by means of a set-screw, U, passing through the weight and bearing on the arm T.

Motion is communicated to the pulley D by means of a belt from any convenient source, and transmitted from pulley C by a belt, K, 15 to the saw arbor or shaft G, as will be readily understood upon referring to Fig. 1.

Some of the advantages of this construction may be secured by applying the counter-weight directly to frame F and arranging it in such 2c relation thereto as to pass a given line, and to act in reverse directions, according as it is to one or the other side of said line; but the construction and arrangement shown and described is preferred. The frame is pushed 25 backward until the weight passes the center, when it serves to complete the retraction of the frame.

Having thus described my invention, what I claim is—

30 1. In combination with a swinging saw-frame, a counter-balance, and an arm or lever for said counter-balance connected with the swinging frame, substantially as described, the pivot of said arm or lever being located

below the center of gravity and at a point intermediate between the limits of movement of said counter-balance, substantially as and for the purpose explained. 35

2. In combination with a swinging saw-frame, a counter-balance therefor, and an intermediate coupling connecting the frame and the counter-balance, said connection being adjustable, substantially as described, to permit the relative inclinations of the counter-balance and the swinging frame to be regulated or 40 varied at will. 45

3. In combination with hanger A, swinging saw-frame F, provided with yoke R, counter-balance Q, provided with hub P and weight T, and pivoted to hanger A, and band S, passing about the hub P, and having its ends attached, respectively, to opposite ends of the yoke, substantially as shown and described. 50

4. In combination with a hanger or support, a swinging saw-frame, F, provided with a yoke, R, an arm, Q, provided with counter-balance T, and hub P, journaled upon support independent of the swinging frame, a band, S, passing about the hub P, attached at its ends to opposite end of the yoke R, one or 55 both ends of the band being provided with a threaded stem and nut, substantially as and for the purpose set forth. 60
